UNITED STATES PATENT OFFICE.

JOHN H. KELLOGG, OF BATTLE CREEK, MICHIGAN.

DENTAL DEVICE.

1,408,839.

Specification of Letters Patent. Patented Mar. 7, 1922.

Application filed February 11, 1921. Serial No. 444,282.

To all whom it may concern:

Be it known that I, JOHN H. KELLOGG, a citizen of the United States, residing at Battle Creek, county of Calhoun, State of Michigan, have invented certain new and useful Improvements in Dental Devices, of which the following is a specification.

This invention relates to improvements in dental devices.

10 The main objects of this invention are to provide an improved dental device for individual or private use which is highly efficient for cleaning the teeth, is sanitary and is convenient to use.

15 Further objects, and objects relating to structural details will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing forming a part 25 of this specification, in which:

Fig. I is a plan view of the holder portion of my improved dental device.

Fig. II is a detail plan view of my improved dental device assembled for use as a 30 tooth brush or tooth polishing device.

Fig. III is an enlarged detail section through the brush member, the holder being partially broken away.

Fig. IV is a plan view of the brush member as supplied to the user.

Fig. V is a longitudinal section through the brush member on a line corresponding to line 5-5 of Fig. IV.

Fig. VI is a face view of one of the clamping jaws, its shank being partially broken away.

Fig. VII is a detail side elevation of my improved holder with a dental implement gripped therein.

45 In the drawing, similar reference characters refer to similar parts through the several views.

Referring to the drawing, my improved dental device as illustrated comprises a strip 50 of tissue paper or other thin paper which is readily softened when subjected to water, the strip being folded upon itself and its ends 2 folded inward upon a strip 3 of coarsely woven fabric such as cheese cloth.

55 When desired for use, this laminate strip is further folded upon itself as shown in Figs.

II and III. The ends of the strip of paper being folded inwardly upon the strip of fabric is effective in holding the strips in assembled relation, that is, the fabric is thus 60 loosely retained. However, when the superimposed strips are further folded, as shown in Figs. II and III, and the bight of the strip engaged by the holder, the paper and fabric are bound together, so that the paper 65 is effectively supported even when more or less softened and disintegrated.

I provide a holder consisting of the handle 4 having a pair of spring shanks 5 secured thereto, the spring shanks terminating in 70 coacting jaws 6. These jaws are preferably outwardly curved and disposed diagonally of the shanks. The shanks have diverging portions 7 with which the annular slide 8 coacts to clamp the jaws upon the brush 75 member described or upon a dental implement as 9, the implement 9 illustrated being a pointed stick of orange wood.

The jaws are clamped upon the bight portion of the multi-folded strip as shown in 80 Figs. II and III so that the ends may be turned backward over the jaws. In practice I have found that the device is very satisfactory when the brush member when folded in the manner shown in Figs. IV 85 and V is of the dimensions of about four by one and five-eighths inches. This permits further folding to a convenient size by giving it four longitudinal folds and then folding cross wise.

90 By thus folding the fabric is in position to effectively support the paper even when the paper is more or less disintegrated as will result from the moisture and in using the device.

95 My improved dental device is very satisfactory for cleaning and polishing the teeth in lieu of a brush being effective and also being sanitary as a new brush member is employed for each cleaning. The holder member may be employed for either the brush member or the pointed implement 9.

I have illustrated and described my improvements in a form which I have found very satisfactory in use. While the particular holder illustrated is advantageous, it might be considerably modified and still prove very desirable.

Having thus described my invention, what I claim as new and desire to secure by Letters Patent, is:

1. A dental device comprising a strip of

paper and a strip of loosely woven fabric folded together, and a holder comprising a pair of coacting jaws adapted to be clamped upon the multi-folded material and so that its ends may be folded backward over the jaws.

2. A dental device comprising a strip of paper, and a strip of loosely woven fabric folded together so that the paper is supported by the fabric when more or less softened and disintegrated by moisture.

3. A dental device comprising superimposed strips of tissue paper and cheese cloth, folded together in multifolds.

In witness whereof, I have hereunto set 15 my hand and seal in the presence of two witnesses.

JOHN H. KELLOGG. [L.S.]

Witnesses:

GERTRUDE ESTELL,
A. F. BLOESE.
